(57) **CLAIM**

The ornamental design for a diaper cover having animal motif, as shown and described.

DESCRIPTION

FIG. 1 is a front perspective view of a diaper cover having animal motif, showing my new design in use condition, with the broken lines being for illustrative purposes only and forming no part of the claimed design;

FIG. 2 is a top plan view thereof, in open condition;

FIG. 3 is a bottom plan view thereof;

FIG. 4 is a right side elevational view thereof;

FIG. 5 is a left side elevational view thereof;

FIG. 6 is a front elevational view thereof; and,

FIG. 7 is a back elevational view thereof.
